INVENTORS:

BY ATTORNEY

UNITED STATES PATENT OFFICE.

JOHN H. TABLER AND FRANK T. GRACEY, OF NASHVILLE, TENNESSEE.

DEVICE FOR MAKING CIGARETTES.

SPECIFICATION forming part of Letters Patent No. 593,822, dated November 16, 1897.

Application filed February 19, 1897. Serial No. 624,208. (No model.)

To all whom it may concern:

Be it known that we, JOHN H. TABLER and FRANK T. GRACEY, citizens of the United States, residing at Nashville, in the county of Davidson and State of Tennessee, have invented certain new and useful Improvements in a Pocket Cigarette-Making Device; and we do hereby declare the following to be a full, clear, and exact description of the invention, such as will enable others skilled in the art to which it appertains to make and use the same.

Our invention relates to an improved device for making cigarettes; and the main object of our invention is the provision of a device adapted to be applied directly to the bag of tobacco which will make a perfect cigarette in a moment and without wasting the tobacco and which will cost but a trifle, thus introducing an article very much needed and desired by smokers of cigarettes.

The invention consists of a device of novel construction substantially as disclosed herein.

Figure 1 represents a perspective view of the invention. Fig. 2 represents a central longitudinal sectional view, and Fig. 3 represents a side view of a modified form of our invention.

In the drawings, A designates a bag or pouch of well-known construction or form, containing tobacco B, and C designates a cylindrical tube, having its inner end D secured in the mouth of the bag by the bag-closing cords or by a band or collar F, closely fitting in an annular groove G of the tube. In the modified form the tube has a slot H to receive the edge of the paper.

From the foregoing description, taken with the drawings, the manner of using our device is obvious. The tube in normal position is turned down and forms a closure to prevent the tobacco from spilling, and to use the same it is simply necessary to form or shape the wrapper upon the tube by turning or rotating the tube, close the outer end, then draw it out until it is filled sufficiently with tobacco, and the cigarette is completed in a moment.

To smokers who make their own cigarettes this device possesses special advantages, as it can be sold at a trifle or given with the bag of tobacco as a part, and it performs its functions perfectly.

We claim—

1. In combination with a tobacco bag or pouch, the herein-described pocket cigarette-making device adapted to be attached to and detachable from the mouth of said bag or pouch, consisting of the band around which fits the mouth of the bag or pouch, and the cylindrical tube, tobacco-feeder and cigarette-former swiveled to the band and adapted to feed the tobacco into the cigarette-wrapper which is formed in proper shape on the tube and while being drawn off the tube is filled with tobacco.

2. In combination with a tobacco bag or pouch, the pocket cigarette-making device adapted to be attached in or detached from the mouth of said bag or pouch, consisting of the band around which is connected the mouth of the bag or pouch, and a cylindrical cigarette-former and tobacco-feeder swiveled in the band and having a slit in its side adapted to hold an edge of the cigarette-wrapper while being formed on the former and allowing the wrapper to be drawn off as it is filled with the tobacco.

3. A pocket cigarette-making device, consisting of the bag or pouch having means for closing the mouth thereof, a pipe or conduit having at its inner end a flange or collar, a flanged collar surrounding the inner end of the tube and resting upon the flange of the tube or conduit to form a swivel connection for the tube and to receive the mouth of the bag or pouch and form a smooth close joint.

In testimony whereof we affix our signatures in presence of two witnesses.

JOHN H. TABLER.
F. T. GRACEY.
